Henry Hoffman
INVENTOR
BY Victor J. Evans

ATTORNEY

UNITED STATES PATENT OFFICE.

HENRY HOFFMAN, OF OMAHA, NEBRASKA.

WRENCH.

Application filed January 20, 1928. Serial No. 248,204.

My present invention has reference to a spanner wrench for coupling or uncoupling fire hose, and my object is the provision of a wrench for this purpose which may be easily, 5 quickly and securely attached to the lugs of the hose coupling to turn the same to couple or uncouple the hose and which is likewise operable to be quickly brought out of engagement with the coupling.

- 10 A further object is the provision of a spanner wrench for this purpose that includes a handle having a notched end that is received in and pivoted to a lug receiving socket on one end of a curved jaw, the other end of the 15 jaw being provided with an opening for the other lug of the handle, while arranged for sliding movement on the handle there is a spring influenced latch that is engageable with the socket for holding the jaw locked to the 20 handle, when the wrench is in coupling engaging position and further whereby an opposite movement of the latch permits of the swinging of the handle and jaw to bring the wrench out of engagement with the coupling. 25 To the attainment of the foregoing the invention consists in certain other novel features of construction and operative association of parts, one satisfactory embodiment of which is disclosed by the accompanying 30 drawings.

In the drawings:

Figure 1 is a side elevation of my improvement, with parts in section.

Figure 2 is an edge view thereof.

- 35 Figure 3 is a side elevation showing the manner in which the parts of the wrench are operated to release the coupling therefrom.

In the showing of the drawings, my improvement is of a construction to operate 40 upon a hose coupling 1 having lugs 2, but obviously the improvement may be provided with pins or lugs to operate upon couplings having depressions therein for the reception of such pins or lugs.

- 45 The improvement contemplates the employment of a handle 1' having a cross sectionally squared portion 2' formed with a rabbeted end to provide the same with a projecting extension or finger 3. The squared end 2' of the handle 1' is received in a bore or aperture 4 provided in a boss or extension 5 at one end of the curved jaw 6. The outer

wall of the extension is cut away or slotted to the outer end of the socket, and the terminal of the slot is inclined, as at 7. The opposite 55 wall of the socket, and the finger provide a space therebetween for one of the lugs 2 of a coupling 1 and the other end of the jaw 6 is provided with a recess or opening 8 for the second lug 2 of the coupling. The end 2' of the handle 1' is pivotally secured, as at 9, in the jaw extension 5.

Arranged for slidable movement on the handle 1 is the latch member 10 which has a socket entering from its outer end, as indicated by the numeral 12. The inner or bottom wall of this socket is provided with a shoulder 13 that surrounds a squared opening therethrough and through this opening the squared end 2' of the handle 1' passes. 70 Having one end fixed to the handle 1', and exerting a pressure against the shoulder 13 of the slidable latch 10 is a coil spring 14. The latch 10, on one of its faces is formed with a lip extension 15 and this lip is designed for 75 contacting engagement with the outer wall of the extension 5 of the jaw 6.

The spring 14 will at all times urge the latch 10 in the direction of the jaw, so that when the jaw is swung to coupling engaging 80 position on the handle, the lip 15 thereof will engage with one of the walls of the part 5 of the jaw, and thus lock the jaw on the handle. By moving the slidable latch 10 in an opposite direction, the handle may be swung on the 85 jaw and likewise the jaw may be swung on the handle. When the jaw is swung to open position one of the straight edges of the end 2' of the handle 1' will rest on the inclined wall or shoulder 7 in the part 5 of the jaw, so that the 90 coupling may readily be released from the jaw, or the wrench may be brought to position to engage with the coupler.

Having described the invention, I claim:

A spanner wrench for the purpose set 95 forth, comprising a handle having a squared end portion rabbeted to provide the same with a projecting finger, a curved jaw having one of its ends formed with an extension provided with a bore in which the squared end of the handle is received and in which the said end of the handle is pivoted, the outer wall of the perforated extension of the jaw 100 having its upper portion slotted forming an

angle shoulder, and the finger of the handle and the opposite wall of the socket providing a space therebetween, the other end of the jaw having an aperture therethrough, a slidable 5 latch on the handle having a socket portion with a square opening through the bottom through which opening the squared end of

the handle passes, a spring having one end fixed on the handle and exerting a pressure against the shoulder and a projecting lip on 10 one end of the latch for engagement with the socket end of the jaw.

In testimony whereof I affix my signature.
HENRY HOFFMAN.
